UNITED STATES PATENT OFFICE.

JOHN F. GROHOWSKY, OF FORTYFORT, PENNSYLVANIA, ASSIGNOR OF FORTY ONE-HUNDREDTHS TO JAMES J. MURRAY, OF WILKES-BARRE, PENNSYLVANIA.

ELECTRIC SWITCH MECHANISM.

1,126,988.

Specification of Letters Patent.

Patented Feb. 2, 1915.

Application filed July 29, 1912. Serial No. 712,159.

To all whom it may concern:

Be it known that I, JOHN F. GROHOWSKY, a citizen of the United States, residing at Fortyfort, in the State of Pennsylvania, ⁵ have invented a new and useful Electric Switch Mechanism, of which the following is a specification.

The present invention relates to improvements in electric switch mechanisms, the primary ¹⁰ object of the present invention being the provision of a novel form of solenoid actuated switch point and signaling switch mechanism controlled by the core of the solenoid to indicate the relative position of

¹⁵ the switch point at all times.

With the foregoing and other objects in view which will appear as the description proceeds, the invention resides in the combination and arrangement of parts and in ²⁰ the details of construction hereinafter described and claimed, it being understood that changes in the precise embodiment of the invention herein disclosed can be made within the scope of what is claimed without ²⁵ departing from the spirit of the invention.

In the drawings is illustrated an enlarged detail view of the switch point and casing with one of the solenoids shown in section, the switch point being in normal or central ³⁰ position.

Referring to the drawings, the numeral 1 designates the base plate having the two upstanding flanges 2 and 2' which constitute the casing for the switch point 3. The base ³⁵ 1 is provided with a transverse slot 4 through which projects and slides the pin 5 which is connected to the switch point intermediate of its ends and is also connected to the cylindrical rod 6 which constitutes the ⁴⁰ two cores for the oppositely disposed solenoids 9 and 10 respectively, a casing or tube 7 surrounding the rod 6 below the switch point casing 1.

The outer end of each of the respective ⁴⁵ solenoids 9 and 10 is sealed by the cap 11 and in each of the respective caps are fitted

the disks 12 and 14 of insulation, the disk 12 being provided with the tubular sleeve 13 projecting into the bore of its respective solenoid while the disk 14 is provided with the ⁵⁰ centering boss 15 seated within its respective cap 11. Fitted between the respective disks 12 and 14 of insulation, is a metal disk 16, carrying the sleeve 17 in which is mounted the stud 18 normally held in the position ⁵⁵ as shown by means of the spring 19, said stud 18 being metal and constituting a movable member of a circuit controlling switch, the opposed end being the other member of the switch. ⁶⁰

With this construction, it is evident that with the movement of the core 6 to the right as viewed in the drawing, the metal stud 18 of the solenoid 10 will be engaged and the switch formed by these members closed. ⁶⁵

What is claimed is:

A switch actuator, comprising two cylindrical casings, a tube connecting the two, two solenoids, one disposed in each casing, a rod slidably mounted in the tube and forming the cores for both solenoids, two disks of insulation disposed in the outer end of each casing, a metal disk having a concentrically disposed metal sleeve, such metal disk being incased by the two disks of insulation with the sleeve within and insulated from the core of the solenoid, the rim of the end of the sleeve being inturned, a stud slidably mounted within the sleeve with one end ⁷⁰ for projection beyond the tube in the path of its respective end of the rod, and a spring within the sleeve for holding the stud projected, said metal disk, stud and the rod when contacting forming a circuit closer. ⁷⁵

In testimony that I claim the foregoing ⁸⁰ as my own, I have hereto affixed my signature in the presence of two witnesses.
